UNITED STATES PATENT OFFICE.

HOWARD P. ANDERSON, OF ST. LOUIS, MISSOURI.

CAST-STEEL HOPPER FOR HOPPER-BOTTOM CARS.

Application filed April 8, 1922. Serial No. 550,772.

To all whom it may concern:

Be it known that I, HOWARD P. ANDERSON, a citizen of the United States, residing at Saint Louis, Missouri, have invented a certain new and useful Improvement in Cast-Steel Hoppers for Hopper-Bottom Cars, of which the following is a full, clear, and exact description, such as will enable others skilled in the art to which it appertains to make and use the same, reference being had to the accompanying drawings, forming part of this application.

My invention relates to railway rolling stock and in particular to those cars which are adapted to discharge their load through a hopper, either by gravity as in a hopper car or by gravity and manual labor as in a hopper bottom car. It has been customary in cars of this type to build the hopper into the car, uniting the parts of the hopper to the framing of the car during the assembly of the latter. Any defect or irregularity in any of the parts of the hopper or in the adjacent parts of the car body would be likely to interfere with the fitting of the hopper door and the functioning of the hopper door operating mechanism.

In the event of any injury to the hopper, it has been difficult to replace a portion of the hopper or the entire hopper without substantially disassembling the car framework adjacent to the hopper. Owing to the location of the hopper and the work which it is required to perform as well as the provision of doors and operating mechanism, it is desirable that the hopper structure should be as rigid and unyielding as possible. The provision of substantial structural stiffening members in the close clearances of railway cars is often difficult without cutting down the area of the hopper or increasing the length of the distance between trucks. Any change in the construction or dimensions of the car body has generally necessitated redesigning the hopper parts accordingly.

The object of my invention is to eliminate the above-mentioned disadvantages and I accomplish this object by providing a unitary hopper assembly preferably formed from a one-piece casting and adapted to be as-

sembled with the car body proper after completion of the latter.

In the accompanying drawings, which illustrate selected embodiments of my invention,

Figure 1 is a longitudinal section through a hopper bottom car equipped with a cast steel hopper of my improved construction.

Figure 2 is a transverse section through a half of the car taken substantially on line 2—2 of Figure 1.

Figure 3 is a longitudinal section through a hopper car equipped with my integral hoppers.

Figure 4 is a transverse section taken substantially on line 4—4 of Figure 3.

The car shown in Figure 1 is provided with the usual center sills 1, side sills 2, sides 3, and cross beams 4. The hopper is formed by a one-piece casting comprising the inclined bottoms or ends 5, vertical side walls 6 which are offset at 7 and 8 to approach the body side wall 3 and center sill 1, respectively. The inner side of the hopper is provided with an attaching flange 9 and the ends of the hopper are provided with attaching flanges 10. The hopper doors 11 may be cast also or of structural steel, and in either instance reinforced by structural members 12. I prefer to form the hinge butts 13 for the door integral with the inclined ends 5.

The hopper operating mechanism may be of any suitable type, and I illustrate an ordinary winding shaft 14 provided with a ratchet 15 and pawl 16 and door operating chain 17 running over a sheave 18.

It will be noted that this formation of the hopper provides a unitary structure which may be assembled before being applied to the car and providing the proper fitting of doors 11 and insuring thereby rigidity to take care of the strains which may be applied to the hopper. In the car shown, the hopper illustrated will be duplicated upon the opposite side of the car and the members 12 are preferably extended across the car beneath the center sills to unite the doors in both hoppers.

In the hopper car shown in Figures 3 and

4, the car is of the spaced side sill type and the hopper extends substantially across the full width of the car but is duplicated on opposite sides of the longitudinal center of 5 the car and the hopper doors are positioned in the inclined inner ends of the hopper. In this car, the hopper is carried by the side sills 19 and the lower parts of the inclined ends 20 of the car body. The hopper is also 10 secured to the car sides 21. Each of the hoppers is an integral casting provided with projections 22 forming hinge butts, offset side walls 23, attaching flanges 24 and 25 and integral stiffening ribs 28. The doors 15 27 are also cast and provided with integral stiffening ribs 26 and hinge butts 29. These hoppers, like those illustrated in Figures 1 and 2, may be equipped with their doors 27 and assembled, as complete units, with the 20 remainder of the car body. Suitable ribbed openings 30 are formed in the hopper sides for the insertion of pokers or steam pipes and each is provided with a pivoted cover 31. Such hoppers may be made as rigid as 25 desired without any likelihood of interfering with necessary clearances. In such structures the metal may be disposed as desired and, therefore, such structures not only possess greater inherent strength for a given 30 weight than the hoppers previously constructed, but add considerably to the rigidity of the car body, bracing the latter at one of its weakest points. Variations in the 35 width or length of the car body may be accommodated by corresponding variations in the pattern for the hopper casting.

I contemplate the usual modifications in the commercial development of my invention, without departing from the spirit

thereof, as expressed in the following 40 claims.

I claim:

1. In a hopper for railway cars, a one-piece casting comprising relatively inclined bottom walls, vertical side walls, and door 45 hinge butts.

2. In a hopper bottom railway car, a hopper comprising an inclined bottom, side walls, attaching flanges, and stiffening ribs, all cast integrally. 50

3. A hopper bottom railway car comprising a car body of structural steel, and a cast steel hopper having a discharge chute of substantially smaller horizontal area than the floor area of said body and having 55 integral offset sides adapted to be secured to the sides of said body.

4. In a hopper bottom railway car, a side wall, a center sill, and a one-piece cast hopper located below and between said side and sill and having integral portions extending upwardly and outwardly to engage said side and sill, and doors mounted on said hopper. 60

5. In a railway car, a one-piece cast hopper for railway cars comprising inclined 65 bottom walls, and vertical side walls offset to engage disaligned portions of a car framing.

6. A hopper bottom railway car comprising a car body of structural steel, and a 70 rigid one-piece cast hopper with doors and door operating mechanism mounted thereon and adapted to be applied to said body as a unit.

In testimony whereof I hereunto affix my 75 signature this 1st day of April, 1922.

HOWARD P. ANDERSON.
